TRUING AND BALANCING DEVICE FOR FACE
TYPE DIAMOND GRINDING WHEELS

Elmer Speicher, Birmingham, Mich.

Application February 24, 1951, Serial No. 212,636

5 Claims. (Cl. 51—168)

1

This application is a continuation in part of my earlier filed application, Serial No. 183,800, filed September 8, 1950, now Patent No. 2,546,529 dated March 27, 1951.

This invention relates to a truing and balancing device for a face type diamond grinding wheel, and more particularly to a novel construction associated with the grinding wheel by which the grinding surface thereof may be arranged in a plane at right angles to its axis of rotation.

It is the object of the present invention to provide an unusual and simplified construction in conjunction with a face type diamond grinding wheel to permit truing of the same.

It is a further object of the present invention to provide a balancing means in association with the truing means for minimizing vibration of said grinding wheel during rotation.

These and other objects will be seen from the following specification and claims in conjunction with the appended drawing in which—

Fig. 1 is a front elevational view of the grinding wheel.

Fig. 2 is a section on line 2—2 of Fig. 1, of the face type diamond grinding wheel as mounted upon its driving spindle, fragmentarily shown, there being a truing indicator provided.

Fig. 3 is a similar view illustrating a slight variation of the construction shown in Fig. 2;

Fig. 4 is another variation, being a similar view to that shown in Figs. 2 and 3; and Fig. 5 is another variation, being a similar view to Fig. 4.

It will be understood that the above drawing illustrates merely a preferred embodiment of the invention and that other embodiments are contemplated within the scope of the claims hereinafter set out.

Referring to the drawing the present face type diamond grinding wheel includes the circular plate 11 having a central depression 11' and corresponding thereto the central plate 12.

There is provided upon the peripheral portion of said grinding wheel an annular abrasive ring 13 which is intimately bonded and secured to circular plate 11 and which includes a conventional diamond abrasive surface wherein finely divided diamond particles are secured in the ring form 13 as shown in Figs. 1 and 2.

The present diamond grinding wheel 11—12—13 has a central aperture to receive the central projecting stem 14 of the rotatable wheel driving spindle 15, said spindle having an annular flange 16 adjacent its outer end and arranged at the inner end of the stem 14 as shown in Fig. 2.

Circular back plate 17 has a central opening which similarly receives the stem 14 after which the central plate 12 of the grinding wheel is positioned upon said stem and immovably secured

thereon by the nut 22 which engages the threaded portion 21 on the outer end of said stem.

The back plate 17 of the grinding wheel assembly has a plurality of spaced circularly arranged tapped openings within which are threadably projected screws 18 as shown in Figs. 1 and 2, there being suitable clearance openings 28 formed in the wheel element 12.

In setting up the grinding wheel for testing the face 13 to determine whether all points upon its outer surface lie in the same plane at right angles to the axis of rotation of the spindle 15, said grinding wheel is arranged as shown in Fig. 2 with a suitable indicator 23 being provided. Said indicator is mounted upon a bracket 25 and includes the rotatable indicator arm 24, the lateral extension 26 and the actuating arm 27 which is arranged normally of the outer surface of the grinding surface 13. By setting the indicator with respect to and in slight contact with the surface of the grinding wheel, rotation of the latter will indicate whether its surface is true, and whether all points upon its surface lie in a plane normal to the axis of rotation of the driving spindle 15.

Variations in the surface 13 are corrected by adjusting the screws 18 selectively so that the inner ends thereof are in operative engagement with the inner surface of the flange 16. These screws are turned placing portions of the flange 16 under a slight bending moment until the wheel is so adjusted that rotation thereof with respect to the indicator arm 27 will show little or no variation on the indicator arm 24 with respect to the dial of said indicator. The clearance openings 28 are spaced and circularly arranged within the wheel element 12 to provide access to the screws 18 and to permit their adjustments such as by a socket wrench or the like.

When the grinding wheel has been properly adjusted so that its outer grinding surface 13 lies in a plane at right angles to the axis of rotation of spindle 15, then said grinding wheel has been properly trued, as shown by indicator 23.

Normally the grinding wheel is not completely balanced, and upon rotation thereof certain vibrations may be set up. This is counteracted and overcome by the slight variation shown in Fig. 3 of the drawing, by applying one or more of the nuts 19 to the screws 18 placing the same selectively and locking the same in position upon one or more of the screws 18 by the lock nuts 20 which are also threaded upon the corresponding screw. It will be noted that the nut or nuts 19 are spaced from the interior wall of the central plate 12 of the grinding wheel so as not to interfere with the setting of the screw with respect to flange 16 and the back plate 17. Similarly

clearance openings 28 are provided in plate 12 in order to receive the screws 18' and to permit their adjustment.

By the construction shown in Fig. 3 there is provided a simplified truing and balancing device for the face type diamond grinding wheel such as is shown in the drawing.

Fig. 4 illustrates another variation of the structure shown in Fig. 2 but wherein the clearance openings 28 of the wheel 12 may be omitted and the screws 18'' are employed, being threaded through spaced circularly arranged tapped openings in the spindle flange 16. The inner ends of screws 18'' are adapted to operatively bear against the back plate 17 placing the same under such tension at selected points by said screws as to effectively align the grinding surface 13 of the grinding wheel, in the same manner as above described with respect to Fig. 2.

Furthermore the grinding wheel may be balanced by the application of one or more nuts 19 the same as in Fig. 3 with accompanying lock nuts 20 for setting nuts 19 in the desired adjusted position.

It is contemplated that under some conditions in the embodiment shown in Fig. 4 the circular back plate 17 may be omitted so that the rear surface of the grinding wheel bears directly against the forward flat surface of the flange 16 on spindle 15. Accordingly the inner ends of the screws 18'', threaded through flange 16, would operatively bear against the wheel 12, and by this arrangement the abrasive surface 13 of the grinding wheel 11 could be properly aligned.

The variation shown in Fig. 5 is similar to that shown in Fig. 4 except that flange 16 is of slightly less diameter and the socket headed screws 18''' extend through back plate 17 for operative adjusting engagement with the rear surface of wheel 12.

A plurality of spaced circularly arranged threaded openings are formed in back plate 17 to receive screws 18'''. In a similar fashion balancing nuts 19 and lock nut 20 are adjustably positioned selectively on some of the screws 18'''.

Having described my invention reference should now be had to the claims which follow for determining the scope thereof.

I claim:

1. In combination, a face type diamond grinding wheel having an annular flat abrasive surface at right angles to its axis of rotation, a rotatable spindle upon which said wheel is centrally mounted and secured, a flat back plate secured upon said spindle and arranged at a right angle to its axis of rotation and against which said wheel bears, and a plurality of spaced circularly arranged set screws threadably projected through said back plate with their inner ends operatively engaging said spindle to the extent that the outer face of said grinding surface lies in a plane at right angles to the axis of rotation of said spindle, said grinding wheel having a plurality of spaced circularly arranged openings into which said screws loosely extend.

2. In combination, a rotatable spindle, a central stem projecting axially therefrom, a circular back plate mounted upon said stem and arranged at right angles to the axis of said spindle, a face type diamond grinding wheel having an annular flat abrasive surface at right angles to its axis of rotation mounted and secured upon said stem and bearing against said back plate, said wheel having a plurality of spaced circularly arranged

apertures, and a plurality of spaced circularly arranged set screws within said apertures threadably extending through transverse threaded apertures in said back plate and operatively bearing against said spindle for adjusting the inner face of said back plate with respect to said spindle so that said grinding surface lies in a plane at right angles to the axis of rotation of said spindle.

3. In combination, a rotatable spindle having a circular flange adjacent one end thereof at right angles thereto, a central stem projecting axially therefrom, a circular back plate mounted upon said stem and bearing against said flange, a face type diamond grinding wheel having an annular flat abrasive surface at right angles to its axis of rotation mounted and secured upon said stem and bearing against said back plate, and a plurality of spaced circularly arranged set screws within openings in said grinding wheel and threadably extending through threaded apertures in said back plate adjustably and operatively bearing against said flange for adjusting said back plate with respect thereto so that said grinding surface lies in a plane at right angles to the axis of rotation of said spindle.

4. In combination, a rotatable spindle having a circular flange adjacent one end thereof at right angles thereto, a central stem projecting axially therefrom, a circular back plate mounted upon said stem and bearing against said flange, a face type grinding wheel having an annular flat abrasive surface at right angles to its axis of rotation mounted upon said stem and bearing against said back plate, a plurality of spaced circularly arranged set screws within openings in said grinding wheel and threadably extending through threaded apertures in said back plate adjustably and operatively bearing against said flange for adjusting said back plate with respect thereto so that said grinding surface lies in a plane at right angles to the axis of rotation of said spindle, said stem being exteriorly threaded, and a nut mounted upon said stem and operatively bearing against said grinding wheel for securing the same on said spindle.

5. In combination, a rotatable spindle, a central stem projecting axially therefrom, a circular back plate mounted upon said stem and arranged at right angles to the axis of said spindle, a face type diamond grinding wheel having an annular flat abrasive surface at right angles to its axis of rotation mounted and secured upon said stem and bearing against said back plate, a plurality of spaced circularly arranged set screws loosely within openings in said wheel and threadably extending through transverse threaded apertures in said back plate and operatively bearing against said spindle for adjusting the inner face of said back plate with respect to said spindle so that said grinding surface lies in a plane at right angles to the axis of rotation of said spindle, and nuts selectively mounted and secured upon some of said set screws for balancing said wheel against vibration upon rotation thereof.
